UNITED STATES PATENT OFFICE.

CLARENCE J. WHITACRE, OF JANESVILLE, WISCONSIN, ASSIGNOR TO GENERAL MOTORS CORPORATION, OF DETROIT, MICHIGAN, A CORPORATION OF DELAWARE.

HOLDER FOR STARTING CRANKS.

Application filed August 21, 1922. Serial No. 533,442.

To all whom it may concern:

Be it known that I, CLARENCE J. WHITACRE, a citizen of the United States, and a resident of Janesville, county of Rock, and 5 State of Wisconsin, have invented certain new and useful Improvements in Holders for Starting Cranks, of which the following is a full, clear, concise, and exact description, such as will enable others skilled 10 in the art to which the invention relates to make and use the same, reference being made therein to the accompanying drawing, which forms a part of this specification.

My invention relates to starting cranks 15 for use particularly with farm tractors driven by internal combustion engines for turning the engine over manually when it is to be started, although the same is also capable of use with automobiles, trucks and 20 similar motor driven vehicles; and the object thereof is to provide a holding member or device for holding the starting crank in an upright position, with its handle up and away from the ground, when the crank is 25 not being used to start the engine.

A further object of my invention is to provide a pivotally supported swinging starting crank holding member for the purpose stated which can under no circumstances interfere with the operation of the 30 crank; the construction and arrangement thereof being such that it will be lifted and swung out of the way by the crank when the same is operated, even though said holding member be not swung into a position 35 out of the path of the crank preliminarily to the starting of the engine as it should be when the engine is about to be started.

In the drawing accompanying and forming 40 a part of this specification, and wherein the preferred embodiment of my invention is illustrated:

Figure 1 is a fragmentary view showing the front end of a tractor or similar vehicle 45 in elevation, and as seen from a position in front thereof, the same being equipped with my invention.

Figure 2 is a similar view showing the position of the parts when the starting crank is being held in an upright position 50 by my invention.

Figure 3 is a view corresponding with Figure 1, but showing the parts in side elevation.

55 Figure 4 is a view showing my invention

by itself and apart from a vehicle, and in plan and upon a larger scale.

Figure 5 is a view corresponding with Figure 4, but showing my invention in side elevation.

Referring now to the drawing, the reference numeral 6 designates a conventional radiator structure of a motor driven vehicle; and 7 designates a starting crank the inner end 8 of which is adapted to engage 65 the crank shaft of the engine which drives the vehicle when it is to be started by hand, the crank extending forward beyond the front of the radiator and having a handle portion 9 to be grasped by the operator in 70 starting the engine.

The radiator illustrated is of the type or class wherein a cellular core portion 10 and a lower water chamber 11 are secured together by spaced fastening bolts 12 and, 75 while my invention is not directly concerned with any particular radiator structure it does, in its more specific aspect, involve a radiator having core and water chamber portions secured together by fastening bolts substantially as illustrated in the drawing.

Secured to the radiator structure preferably by one or more bolts 12 which fasten the core and the lower water chamber portions thereof together is a base member 13 made, for example, from thin plate metal stock; and which base is provided with aligned bearings 14, 14 adjacent its ends which, in the preferred embodiment of my 90 invention illustrated, are formed by bending projecting lugs of the sheet metal blank from which the base is formed into hollow cylindrical form about end supporting portions of the swinging crank holding element of my invention, to be next described.

The immediate crank holding member of my invention is shown as made from a piece of round bar iron bent to provide aligned end bearing portions 15, 15 which fit loosely 100 within the bearings 14, 14 of the base member 13 to thereby support said holding member so that it is free to swing up and down about the pivotal connections thus provided, and arms 16, 16 extending at about right angles to said end portions and which are connected together at their outer ends by a curved portion 17 offset from the axis of said bearing portions and which forms a recess within which the crank arm 7 may 110

lie; and the sides of which recess will act to hold the crank in a substantially vertical position, as shown in Figure 2, if the crank is first placed in such a position and the said member then swung downward and into the position indicated in said figure. The plane of the curved portion 17 is preferably inclined relative to the plane of the arms 16, as best shown in Figure 5, so that the said curved portion will lie nearly horizontal when the crank is being held upright. When the engine is to be started the crank holding member is swung upward about the pivotal connections between the same and its supporting plate to thereby release the crank and permit its free end to be engaged with the crank shaft of the engine, whereupon and upon turning the crank the engine may be started manually, as will be appreciated.

When the crank holding member is swung upward to release the crank it should be swung into the extreme position indicated at —A— in Figure 3, in which it rests against the front of the radiator and remains out of the path of the crank during the starting position. If, however, the operator fails to swing said holding member past a vertical position, or if it falls into the position shown at —B—, Figures 1 and 3, said holding member will nevertheless not interfere with the starting of the engine; for when said member is in said last mentioned position the outer ends of the arms 16 extend beyond the crank, and the said member will be swung upward by engagement of the crank with the under sides of the arms thereof as the crank is rotated.

If the crank 7 is operated rapidly the crank holding member may be swung upward with such velocity that it will be thrown into the extreme position indicated at —A— in Figure 3, in which position it may remain until the starting is accom-

plished and the operator swings said member downward to hold the crank in an upright position, as shown in Figure 2; while if the rotation of the crank is slower the holding member will follow the crank and be lifted upon each rotation thereof. As a matter of course if extremely slow motion is assumed the holding member might return from an upward swing quick enough to engage the crank before it passes beyond the recess provided by the curved connecting portion 17 of the holding member, thus arresting the motion of the crank before the starting of the engine is effected. At all ordinary speeds of rotation, however, the crank will pass the recess before the holding member has time to return from the upward swing imparted to it by the crank. As a matter of fact said holding member is commonly thrown clear into the extreme position —A— upon each rotation of the crank, although it commonly rebounds and returns past its vertical position and falls down over the crank, to be again lifted upon the next rotation thereof, as will be understood.

Having thus described and explained my invention, I claim and desire to secure by Letters Patent:

In a crank holding device of the class described and in combination with a rotatable starting crank, a vertically swinging holding member located above said crank and extending into the path of movement thereof, and having an inclined side or arm adapted to be engaged by said crank, and a recess within which said crank may lie; and means for pivotally supporting said holding member in such a manner that it is free to swing as aforesaid when the inclined side thereof is engaged by said starting crank.

In testimony whereof I affix my signature.

CLARENCE J. WHITACRE.
